Primary Examiner — Karen E Eldridge Powers

(57) CLAIM

I claim the ornamental design for a checkerboard cowboy hat, as shown and described.

DESCRIPTION

FIG. 1 is a front perspective view of a checkerboard cowboy hat showing my new design;

FIG. 2 is a right side perspective view thereof, the left side view being identical thereto;

FIG. 3 is a back perspective view thereof;

FIG. 4 is a bottom view thereof; and,

FIG. 5 is a front view thereof.
